(57) **CLAIM**

The ornamental design for a lower or leg section of massage chair, as shown and described.

DESCRIPTION

FIG. 1 is an environmental, front, elevational view of a lower or leg section of massage chair showing a new design; FIG. 2 is a right side, elevational view thereof;

FIG. 3 is a left side, elevational view thereof;

FIG. 4 is a bottom, elevational view thereof;

FIG. 5 is an environmental, front, elevational view thereof, showing the lower or leg section being attached or secured to a massage chair;

FIG. 6 is an environmental, rear, elevational view thereof, showing the lower or leg section being attached or secured to a massage chair;

FIG. 7 is an environmental, right side, elevational view thereof, showing the lower or leg section being attached or secured to a massage chair;

FIG. 8 is an environmental, left side, elevational view thereof, showing the lower or leg section being attached or secured to a massage chair;

FIG. 9 is an environmental, right side, elevational, perspective view thereof, showing the lower or leg section being attached or secured to a massage chair; and,

FIG. 10 is an environmental, left side, elevational, perspective view thereof, showing the lower or leg section being attached or secured to a massage chair.

The broken lines shown in the drawing views are included for illustrative purposes only, and form no part of the claimed design.
